HOIST

Harlow R. Olsen, Minneapolis, Minn.

Application February 3, 1947, Serial No. 726,048

6 Claims. (Cl. 187—10)

1

This invention has relation to a hoist for material, such, for example, as brick or concrete blocks, adapted to be employed for the same general purpose as is the hoist disclosed in my Letters Patent of the United States No. 2,364,547, for Combination hoist and scaffolding, granted December 5, 1944.

An object of the invention is to provide a hoist incorporating features and characteristics of invention adapted to render the hoist an improvement generally over the disclosure of my above identified United States Letters Patent.

A further object is to provide a new and improved hoist wherein will be incorporated various desirable and improved features and characteristics of construction novel both as individual entities of the hoist and in combination with each other.

A further object is to provide a hoist adapted to be moved substantially horizontally along scaffolding, having means for receiving a load, mechanism for causing said means, while supporting or not supporting said load, to be moved selectively upwardly or downwardly, in substantially vertical direction, relative to said scaffolding, and a novel and improved construction and arrangement including longitudinally adjustable uprights adapted to be rested against said scaffolding and to slidably receive said means.

And a further object is to provide in a hoist adapted to be supported for movement to selected location along scaffolding and including a platform, or equivalent, for receiving material, a novel and improved construction and arrangement including longitudinally adjustable uprights along which said platform is adapted to be moved, and devices for moving the platform along said uprights in direction substantially vertically of the scaffolding.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification.

Fig. 1 is a front elevational view of a hoist made according to the invention;

2

Fig. 2 is a side elevational view of said hoist as it would appear from the left side in Fig. 1, the view also disclosing scaffolding and suggesting the manner in which the hoist can be rested against scaffolding;

Fig. 3 is a rear elevational view, on a reduced scale, of the hoist;

Fig. 4 is an enlarged horizontal sectional view, taken substantially on line 4—4 in Fig. 1; and
10 Fig. 5 is an enlarged vertical sectional view, taken substantially on line 5—5 in Fig. 1.

With respect to the drawings and the numerals of reference thereon, 10 denotes a masonry wall, 11 represents scaffolding, which may be of ordinary or preferred construction, adjacent and parallel to said masonry wall, and 12 indicates a hoist designed for use in connection with scaffolding such as 11 and including features and characteristics of the invention.

20 The scaffolding 11 consists of a usual frame 13, adapted to rest upon the ground or other surface, supporting a customary floor 14 of the scaffolding for workmen.

The hoist 12 includes an elongated base 15 supported by spaced apart, aligned wheels 16, 16 at opposite ends of said elongated base. The wheels 16, 16 are arranged tandem, each wheel is rotatably assembled, at 17, with the elongated base, and said wheels 16 desirably may be at the midwidth of said elongated base 15.

25 The elongated base 15 rigidly supports, as at 18, 18, spaced apart uprights, designated 19 and 20, respectively, of said hoist 12. As disclosed, the upright 19 is supported directly above one of the wheels 16, and the upright 20 is situated interiorly of the other wheel 16. The uprights 19, 20 are as shown perpendicular to the elongated base 15 and parallel with each other.

30 Each of the uprights 19 and 20 is constituted as a plurality of telescoping hollow tubular members. More explicitly, the upright 19 consists of a lower hollow tubular member 21 fixedly connected to the elongated base 15, an intermediate hollow tubular member 22 and an upper hollow tubular member 23, and the upright 20 consists of a lower hollow tubular member 24 fixedly connected to said elongated base 15, an intermediate hollow tubular member 25 and an upper hollow tubular member 26. It is to be understood, however, that each of the uprights 19 and 20 can be comprised as two, or more than three, hollow tubular members.

35 A head frame or cross-beam 27, parallel to said elongated base 15, rigidly connects the upper end portions of the upper hollow tubular mem-

bers 23 and 26 of said uprights 19 and 20 to each other and retains said upper hollow tubular members 23 and 26 in spaced, fixed, parallel relation. Stated otherwise, the hoist 12 includes a collapsible rectilinear body constituted as the elongated base 15 supported for longitudinal movement upon the wheels 16, 16, the spaced apart, parallel uprights 19, 20 each consisting of telescoping hollow tubular members a lowermost one of which is rigid with said elongated base, and the head frame or cross-beam 27 perpendicular to said uprights and rigid with uppermost telescoping hollow tubular members of the different uprights, respectively. All of the elongated base 15, the uprights 19, 20 and the head frame or cross-beam 27 lie in a single plane.

The intermediate hollow tubular members 22 and 25 are snugly, vertically slidable in the lower hollow tubular members 21 and 24, respectively, and the upper hollow tubular members 23 and 26 are snugly, vertically slidable in said intermediate hollow tubular members 22 and 25, respectively.

Each of the hollow tubular members of each of the uprights 19 and 20 includes a longitudinally extending slot, each designated 28, and the construction and arrangement are such that the longitudinally extending slots of the hollow tubular members constituting each of said uprights 19 and 20 are in vertical alinement. That is to say, the longitudinally extending slots 28 in the hollow tubular members 21, 22 and 23 of the upright 19 are in vertical alinement, as are also the longitudinally extending slots 28 in the hollow tubular members 24, 25 and 26 of the upright 20. Also, the construction and arrangement are such that the longitudinally extending slots in the hollow tubular members constituting the uprights 19 and 20, respectively, face inwardly at the interior sides of said uprights 19 and 20 and are in a plane passed longitudinally and centrally through both uprights. Stated otherwise, the longitudinally extending slots in the hollow tubular members of the different uprights 19 and 20, respectively, face each other and lie in a plane passed vertically and diametrically through all of the hollow tubular members of both of said uprights 19 and 20.

The opposite side walls bounding or defining each of the longitudinally extending slots 28 of each of the uprights 19 and 20 constitute a guide way 29 of the hoist which faces inwardly and extends longitudinally of the corresponding upright. That is, the opposite side walls bounding or defining the longitudinally extending slots of the different uprights 19 and 20, respectively, together provide oppositely disposed guide ways 29, 29 of the hoist which face each other.

A platform 30, for receiving material, such, for example, as brick or concrete blocks, situated between the uprights 19, 20 to extend to position forwardly of said uprights, is mounted for slideable movement in direction longitudinally of the uprights. The platform 30 as disclosed is integral with a vertical support 31 for said platform, and oblique reinforcing elements 32 extend between and are integrally connected with said platform and vertical support. The vertical support 31 desirably is cut away at its interior 33.

Guide strips 34, 34, including a guide strip slidably disposed in each of the guide ways 29, 29, are integral with and extend exteriorly from the opposite side edges of the vertical support 31 substantially in the plane of said vertical support. The guide strips 34, 34 are substantially

perpendicular to the platform 30, and are of sufficient length to effectively retain said platform in substantially perpendicular relation to the uprights 19, 20. Desirably, said guide strips 34, 34 will be of thickness slightly less than a dimension representing the width of each longitudinally extending slot 28, and all of the longitudinally extending slots 28 may be substantially of equal width. As disclosed more clearly in Figs. 4 and 5, the upper marginal portions of the guide strips 34, 34, as well as the upper marginal portion of the vertical support 31, are offset, as represented at 35, in direction away from the platform 30.

A cable 36, secured, as at 37, to an upper, central portion of the vertical support 31, extends upwardly over a sheave 38 rigidly supported, as at 39, upon the head frame or cross-beam 27 at location substantially midway between the uprights 19, 20, and then downwardly over a sheave 40 rigidly supported, as at 41, at the exterior side of the upright 20 upon an extension of said head frame or cross-beam 27. The end portion of the cable 36 opposite the vertical support 31 is wound upon and about a winch 42 rigidly supported, as at 43, upon a portion of the elongated base 15 at the exterior side of said upright 20.

An electric motor 44, for operating the winch 42, is mounted, as at 45, upon said elongated base 15 at the side of said winch opposite the upright 20. A casing 46, between the electric motor 44 and the winch 42, houses gear reducing mechanism (not shown). An electric motor driven shaft 47 is adapted to drive gear reducing mechanism in the casing 46, and a horizontal shaft 48 is for drivingly connecting said gear reducing mechanism with the winch 42. Obviously, the platform 30 will be caused to move longitudinally of the hoist in response to actuation of the electric motor 44. The construction and arrangement can be such that said electric motor and winch will cause the platform to remain in any position to which moved by the electric motor. The motor employed can be of ordinary construction adapted to rotate in a single direction. In such an instance, the platform 30 would be elevated in response to operation of the motor and allowed to become depressed by gravity when released by the motor and winch. Or, the motor employed could be of type adapted to be rotated in either of opposite directions.

The hollow tubular members are adapted to be fixed at any adjusted position relative to each other which may be selected, thus to make possible longitudinal adjustment of the uprights 19 and 20, respectively. Stated differently, the uprights 19 and 20 can be made longer or shorter, as may be desirable in particular instances.

As disclosed, each of the intermediate hollow tubular members 22 and 25 of the different uprights 19 and 20, respectively, includes spaced apart, vertically aligned, rectilinear slots 49. The rectilinear slots 49 in the hollow tubular members 22 and 25, respectively, will be similarly spaced so that no matter what may be the position of vertical adjustment of said hollow tubular members 22 and 25 there will be horizontally aligned rectilinear slots.

The upper portion of each of the lower hollow tubular members 21 and 24 hingedly supports, as at 50, a locking element 51 adapted to be swung in a horizontal plane and including spaced apart, vertically aligned, inwardly extending locking lugs 52, 52. In the disclosure as made, the locking lugs 52, 52 are spaced at the same distance apart as are the rectilinear slots 49, and

the free marginal portions of said locking lugs 52, 52 are of curvilinear conformation, as will be clear from Fig. 4. The lower hollow tubular members 21 and 24 include spaced apart, vertically aligned, rectilinear slots at the elevation of the locking lugs 52, 52, and said locking lugs are adapted to be passed through said rectilinear slots in said lower hollow tubular members 21 and 24 and removably inserted in adjacent rectilinear slots 49 in the hollow tubular members 22 and 25, thus to cause the intermediate hollow tubular members to be fastened in fixed relation to the lower hollow tubular members. A keeper for each of the locking elements 51 is constituted as an arm 53 rigid with the corresponding hollow tubular member, 21 or 24, as the case may be, having an aperture 54 for receiving a bolt 55 adapted to be removably inserted in said aperture at the rear of vertically spaced ears 63 upon the corresponding locking element 51 and above and below said keeper 53, thus to preclude the possibility of the locking lugs 52, 52 becoming accidentally displaced from the rectilinear slots 49.

Also, each of the upper hollow tubular members 23 and 26 of the different uprights 19 and 20, respectively, includes spaced apart, rectilinear slots 49, equivalent to the rectilinear slots already described and for the same purpose, and the upper portion of each of the intermediate hollow tubular members 22 and 25 hingedly support a locking element 51, equivalent to the locking elements already described and for the same purpose.

Locking lugs 52 upon the locking elements 51 carried by the intermediate hollow members 22 and 25 are adapted to be inserted in and removed from the rectilinear slots 49 in the upper hollow tubular members in substantially the manner as set forth in connection with the locking lugs upon the locking elements carried by the lower hollow tubular members 21 and 24, and keepers 53 are provided for said locking elements upon said intermediate hollow tubular members.

In the illustrated embodiment of the invention, the rectilinear slots 49 in the upper hollow tubular members 23 and 26 are spaced apart the same distance as are the rectilinear slots 49 in the intermediate hollow tubular members 22 and 25, and the construction and arrangement are such that the lugs 52, 52 upon the locking elements 51 carried by the lower hollow tubular members 21 and 24 can be inserted in rectilinear slots in the upper hollow tubular members while also in rectilinear slots in the intermediate hollow tubular members, thus to be capable of retaining all of the hollow tubular members of the uprights 19 and 20 in fixed relation to each other.

The upper end portion of each of the lower hollow tubular members 21 and 24 includes means, denoted 56, for precluding removal of the intermediate hollow tubular members 22 and 25 from said lower hollow tubular members, and the upper end portion of each of said intermediate hollow tubular members includes means, also denoted 56, for precluding removal of the upper hollow tubular members 23 and 26 from the intermediate hollow tubular members.

Cross-bracing between and permanently assembled with the lower hollow tubular members 21 and 24 is represented at 57, cross-bracing between and removably assembled with the intermediate hollow tubular members 22 and 25 is indicated at 58, and cross-bracing adapted to be situated between and removably assembled with

the upper hollow tubular members 23 and 26 is designated 59. As shown, the cross-bracings 58 and 59 are adapted to be removably secured between their corresponding hollow tubular members by headed and nutted screw bolts 60. Of course, either one of the cross-bracings 58 or 59 could be so employed that its upper portion was secured between the upper hollow tubular members 23 and 26 while its lower portion was secured between the intermediate hollow tubular members 22 and 25, as, for instance, when said upper hollow tubular members 23 and 26 were but partially extended from said intermediate hollow tubular members 22 and 25.

Threaded rods 61 extending outwardly from the permanent cross-bracing 51, adapted to removably receive nuts 62, can be employed to retain the removable cross-bracings 58 and 59 upon the hoist when said cross-bracings 58 and 59 are out of use. See Figs. 2, 3 and 5.

It will be evident that the hoist 12 can be readily and easily moved along the full length of the scaffolding 11. In practical use, the hoist can be manipulated along the scaffolding by a workman standing on the scaffolding floor 14. The hoist will be disposed in oblique relation to the scaffolding so that the uprights rest against the forward edge of the scaffolding floor. A workman situated upon the scaffolding can grasp the hoist and cause it to be rolled along on the wheels 16, 16. And a workman adjacent a lower portion of the scaffolding can cause said hoist to be moved in direction longitudinally of the elongated base 15 just as readily and easily as can a workman situated upon said scaffolding.

Also it will be evident that the uprights 19 and 20 can be adjusted as to length, or longitudinally, thus to suit various different working conditions. For a relatively low scaffolding, the arrangement may be about as in Fig. 2 of the drawings, for a comparatively higher scaffolding the intermediate hollow tubular members 22 and 25 may be extended to greater or less extent from the lower tubular members 21 and 24, and for a still higher scaffolding the upper hollow tubular members 23 and 26 also may be extended to greater or less extent from said intermediate hollow tubular members 22 and 25.

Obviously, the platform 30 can be readily and easily raised and lowered no matter what may be the length of the uprights 19 and 20 and no matter at what position the hoist may be situated along a length of scaffolding.

The hoist, while adapted to be supported against scaffolding which varies in height, for movement to selected location along the scaffolding, is, at the same time, equipped with a platform for receiving material and with mechanism for raising and lowering the platform.

What is claimed is:

1. A hoist comprising a base, spaced apart uprights upon said base each constituted as a plurality of telescoping hollow tubular members adapted to be adjusted longitudinally relative to each other, said telescoping hollow tubular members of each of said uprights, respectively, including longitudinally extending vertically aligned slots and the longitudinally extending, vertically aligned slots of the telescoping hollow tubular members of the different uprights providing guide ways in facing relation to each other at the interior sides of said different uprights, means for fastening the telescoping hollow tubular members constituting each of said uprights in fixed relation to each other at any one of several dif-

ferent positions of longitudinal adjustment of said telescoping hollow tubular members, guide members mounted for slidable movement along said guide ways, a platform rigid with said guide members, and mechanism for causing said guide members and platform to be moved along said guide ways.

2. The combination as specified in claim 1, and a cross-beam spaced from said base and rigid with a telescoping hollow tubular member of each of said uprights.

3. A hoist comprising a base, spaced apart uprights upon said base each constituted as a plurality of telescoping members adapted to be adjusted longitudinally relative to each other, the telescoping members of each of said uprights including longitudinally extending, alined slots, means for fastening the telescoping members constituting each of said uprights in fixed relation to each other at any one of several different positions of longitudinal adjustment of said telescoping members, means mounted for slidable movement along said longitudinal slots, a platform rigid with said means, and mechanism for causing said means to be moved along said telescoping members.

4. A hoist comprising a base, spaced apart uprights upon said base each constituted as a plurality of telescoping members adapted to be adjusted longitudinally relative to each other, the telescoping members of each of said uprights including longitudinally extending, alined slots, means for fastening the telescoping members constituting each of said uprights in fixed relation to each other at any one of several different positions of longitudinal adjustment of said telescoping members, a cross beam spaced from said base and rigid with a telescoping member of each of said uprights, means mounted for slidable movement along said longitudinal slots, a platform rigid with said means, and mechanism for

10
1520
25

causing said means to be moved along said telescoping members.

5. A hoist comprising a base, spaced apart uprights upon said base each constituted as a plurality of telescoping hollow tubular members adapted to be adjusted longitudinally relative to each other, said telescoping hollow tubular members of each of said uprights including longitudinally extending, alined slots and the longitudinally extending, alined slots of the telescoping hollow tubular members of the different uprights providing guide ways at opposite sides of said hoist, means for fastening the telescoping hollow tubular members constituting each of said uprights in fixed relation to each other at any one of several different positions of longitudinal adjustment of said telescoping hollow tubular members, guide members mounted for slidable movement along said guide ways, a platform rigid with said guide members, and mechanism for causing said guide members and platform to be moved along said guide ways.

6. The combination as specified in claim 5, and a cross beam spaced from said base and rigid with a telescoping hollow tubular member of each of said uprights.

HARLOW R. OLSEN.
